UNITED STATES PATENT OFFICE

157,244

CHAIN FOR A NECKLACE OR SIMILAR ARTICLE

Frederick A. Dieterich, Maplewood, N. J., assignor
to Universal Chain Co. Inc., Maplewood, N. J.,
a corporation of Rhode Island

Application September 21, 1949, Serial No. 5,124

Term of patent 14 years

(Cl. D45—16)

To all whom it may concern:

Be it known that I, Frederick A. Dieterich, a citizen of the United States of America, and a resident of Maplewood, in the county of Essex and State of New Jersey, have invented a new, original, and ornamental Design for a Chain for a Necklace or Similar Article, of which the following is a specification, reference being had to the accompanying drawing, forming a part thereof.

Figure 1 is a top plan view of a chain showing my new design, with portions broken away.

Figure 2 is a side elevational view of the chain, the other side being the same.

Figure 3 is a bottom plan view thereof, and Figure 4 is an end elevational view of the chain approximately on the plane of the line 4—4 of Figure 1, the other end being the same.

I claim:

The ornamental design for a chain for a necklace or similar article, as shown.

FREDERICK A. DIETERICH.
